UNITED STATES PATENT OFFICE

1,938,024

ROOF STRUCTURE

James H. Keeffe, Sioux City, Iowa

Application April 30, 1930. Serial No. 448,605

2 Claims. (Cl. 108—23)

This invention appertains to new and useful improvements in roof structures, and more particularly to a novel arch unit built up of a multiplicity of elongated elements.

5 The principal object of the invention is to provide an arch structure for curved roofs, the same being of box construction to insure lightness without sacrificing any of its load resisting ability.

Another important object of the invention is to 10 provide a novel arch structure and supporting pillars for the ends thereof, whereby the ends of the arch structure, are firmly fixed against the liability of shifting.

During the following specification and claims, 15 other important objects and advantages of the invention will readily become apparent to the reader.

In the drawing:—

Figure 1 represents a side elevational view of 20 the novel arch structure mounted upon the pillars.

Fig. 2 represents an enlarged fragmentary side elevation view of the arch structure.

Fig. 3 represents a vertical sectional view taken 25 substantially on the line 3—3 of Fig. 2.

Referring to the drawing wherein like numerals designate like parts, it can be seen that the novel arch structure is built up of an upper section 5 and a lower section 6, each built-up preferably of 30 the same number of relatively thin timber lengths 6. Between the sections 5 and 6, are interposed the spaced piles 7—7 built up of elongated timbers 8, each of which is substantially square in cross section.

35 Of course the specific cross section, thickness and width of these timbers may vary in accordance with the nature and construction of the arch for different purposes.

The foregoing sets forth the timbers that are 40 employed and the relation in which they are placed with respect to each other. In the practical assembly of these timbers a template should be employed, so as to acquire the proper curvature of the structure.

45 The timbers are placed on the template and the ends of the timbers are secured to retain the timbers at the curvature defined by the template. To place the upper and lower timbers under compression and tension respectively, the portions of 50 the timbers between the secured ends are secured together at intervals by proceeding inwardly from the secured ends of the timbers toward the middle of the secured timbers. Thus when the arch is removed from the template, the proper curvature will be maintained.

As is clearly shown in Fig. 1, a pillar 10 is provided for each end of the arch structure, and the upper portion of each pillar is provided with steps 11, 12 and 13. It can also be seen that the ends of the arch structure are cut off in a stepped fashion so as to mesh with the steps 11, 12 and 13, of the pillar structures.

Furthermore, a pair of anchor bars 14—14 are provided at each end of the arch structure. These anchor bars 14—14 extend outwardly from each end of the arch structure. These anchor bars may be secured to the arch structure by the same bolts 9 and are preferably bent laterally at the extended end portions, and embedded in the concrete pillar 10 as in the manner substantially shown.

Manifestly, the novel arch structure will be quite practical in the construction of auditoriums, aeroplane hangars, storage buildings, garages, and other analogous building structures. 75 Furthermore, the box-like construction of the arch will render the same light in weight, without sacrificing any of its ability to withstand strain, and stress which may be occasioned during wind storms, etc.

While the foregoing specification sets forth the invention in definite terms, it is to be understood that numerous changes in the shape, size, and materials may be resorted to without departing from the spirit and scope of the claims appended.

Having thus described my invention what I claim as new is:—

1. A method of constructing arches from a pair of elongated members consisting in placing the elongated members in a template, securing the ends of the members together in the template to retain the members at the curvature defined by the template, and securing the portions of the members between said secured ends together at intervals by proceeding inwardly toward the middle of the said secured members from the said secured ends thereof so as to place the upper member under compression and the lower member under tension.

2. An arch structure of box construction comprising an upper and a lower section, each comprising a plurality of elongated lengths of material, an intermediate section comprising a pair of elongated members arranged in spaced parallel relation and interposed between the upper and lower sections, and securing elements disposed through the upper, lower and intermediate sections to secure the same together.
